CLAIM

The ornamental design for a barbecue grill, as shown and described.

DESCRIPTION

FIG. 1 is a front, right and top perspective view of a barbecue grill in a closed condition, showing my new design;

FIG. 2 is a rear, left and bottom perspective view thereof; FIG. 3 is a front, right and top perspective view of a barbecue grill, in an open condition;

FIG. 4 is a front view of a barbecue grill, in a closed condition;

FIG. 5 is a rear view thereof;

FIG. 6 is a left side view thereof;

FIG. 7 is a right side view thereof;

FIG. 8 is a bottom plan view thereof; and,

FIG. 9 is top plan view thereof.

The broken lines shown in the drawings illustrate portions of the barbecue grill that form no part of the claimed design.

1 Claim, 9 Drawing Sheets
